MULTIPLE COILER

Thomas E. Lewis, Jr., Trumbull, Conn., assignor to The Coulter & McKenzie Machine Co., Inc., Bridgeport, Conn., a corporation of Connecticut

Application August 17, 1956, Serial No. 604,677

6 Claims. (Cl. 242—83)

This invention relates to a wire handling apparatus and more specifically to a wire feeding and coiling mechanism for packaging wire in a suitable container.

An object of this invention is to provide a means for handling the feeding and coiling operation of a wire making process in an efficient, rapid and labor saving manner.

Another object of this invention is to provide means whereby a plurality of wire feeding and coiling operations can be carried on simultaneously at maximum efficiency in a minimum of operating space.

These and other advantages are accomplished according to this invention by a wire feeding and coiling apparatus comprising a common frame structure having mounted thereon a plurality of coiling stations which are adapted to be operated off a common drive means. According to this invention each station comprises guide means for guiding a wire emanating from a supply source about a rotary means which casts the wire in a coil and feeds the same into a suitable container secured on a rotatably mounted carrier or turntable located adjacent and below the rotary means, the rotary means and carrier means being connected in driving relationship for relative rotation therebetween. To facilitate removal of the containers as they become full, means are provided for selectively engaging and disengaging the driving connection between each of the carrier means and its respective rotary means, the driving connection being disengaged to cease the rotation of the carrier so that the container may be individually removed or changed therefrom as required without interrupting the feeding and coiling operations at the other stations.

A feature of this invention resides in the provision whereby a plurality of individual feeding and coiling stations are tandemly mounted either in rows or banks of rows so that a maximum number of feeding and coiling operations can be performed in a minimum of space.

Another feature of this invention resides in the provision of vertically disposing the rotary means for rotation about a substantially horizontal axis so that wire looped therearound is fed from the top of the rotary means and into a container mounted for rotation about a substantially vertically disposed axis.

Another feature of this invention resides in an independently actuated selectable means for engaging and disengaging the carrier means in driving relationship with the rotary means to facilitate removal or change of a container without interrupting the operation being carried on at the other stations.

Still another feature of this invention resides in the provision that the improved wire feeding and coiling apparatus is relatively simple in construction, efficient in operation, relatively inexpensive to manufacture and positive in operation.

Other features and advantages will be apparent from the specification and claims when considered in connection with the drawings in which:

Figure 1 is a front elevational view of the improved

2

wire and feeding apparatus having portions thereof broken away.

Fig. 2 is a plan view of the apparatus illustrated in Fig. 1.

Fig. 3 is a fragmentary sectional view taken through one of the feeding and coiling stations of the instant apparatus.

Fig. 4 is a detail plan view of the actuator means as viewed along line 4—4 of Fig. 3.

Fig. 5 is a sectional view taken along line 5—5 of Fig. 3.

Referring to the drawings, the feeding and coiling mechanism according to this invention comprises a frame structure 10 which is common to a plurality of wire feeding and coiling stations 11, each station including a guide means 12 for guiding a strand of wire W from a supply source (not shown) to a rotary means 13 which casts and feeds a wire into a suitable container C supported on a rotating carrier means 14 connected in driving relationship with the rotary means. According to this invention, any suitable number of stations or rows of stations may be arranged on the frame structure. However, it has been discovered that by arranging a plurality of stations tandemly in rows and banking a pair of rows in slightly staggered, back to back relationship on the common frame as shown in Figs. 1 and 2, maximum efficiency can be obtained in a minimum area.

The frame 10 supporting the rows of stations, as shown in Figs. 1 and 2, includes a base 15 on which the carrier means of each station are supported. As best seen in Fig. 3, each carrier means 14 includes a turntable 16 connected to a vertically disposed spindle 17 mounted in suitable bearings 18 for rotatably supporting the turntable on the base for rotation about a vertical axis. A drive shaft 19 horizontally disposed and mounted in suitable end bearings 20 is connected to the turntable 16 through a bevel gear 21 connected to the turntable meshing with a bevel gear 22 connected to the shaft 19. As will be hereinafter described, the shaft 19 is connected in driving relationship with its respective rotary means 13 so that rotation of the latter imparts a relative rotative movement to the turntable 16 and container C supported thereon for receiving the wire. To facilitate packaging of the wire, it will be noted that the container C is provided with a core 23 forming a space between it and the container sides into which the wire is coiled as the container is rotated.

Disposed between and separating the rows of carrier means 14 there is mounted on the base 15 a housing 24 consisting of a pair of vertically spaced side walls 25 and an enclosing top wall 26. Within the housing 24 there is mounted a supporting bracket 27 comprising a pair of elongate spaced plate members 28 or the like extending substantially the length of the housing and forms the means for supporting the rotary means 13 of each station as well as the main drive means 29 for simultaneously actuating the rotary means 13 of each row of stations as will be hereinafter described.

As shown in Fig. 3, the rotary means 13 of each station includes a capstan 30 having a peripheral groove 31 about which the wire W is looped for feeding the same into the container. A roller 32 carried by an arm 33 pivotally mounted on the housing 24 is urged into engagement with the wire looped on the capstan to press it into feeding relation therewith and to provide a cast in the wire to cause it to form coils as the wire is being fed into the container. A shaft 34 connected to the capstan 30 and mounted in suitable aligned bearings 35 in plate members 28 of the bracket supports the capstan for rotary movement in a substantially vertical plane adjacent the side of the container with its axis substantially at the top of the container as shown in Figs. 1 and 2.

As shown, the capstan 30 and turntable 16 of each sta-

tion are connected in driving relationship so that a predetermined relative rotative movement is established therebetween. This is accomplished in the illustrated form of the invention by connecting the capstan 30 to the shaft 19 of the carrier means through a chain or belt 36 threaded over cooperating sprockets or pulleys 37, 38 connected to the capstan 30 and drive shaft 19 respectively. It will be noted that the driving connection between the capstan and its respective carrier means is enclosed within the housing by providing an opening 25a in the spaced walls 25 of the housing for accommodating the inner end 30a of the capstan to which the chain drive 36 is connected. Thus, the hazard of having an exposed driving connection between the capstan and carrier is eliminated.

In the illustrated form of the invention a common drive is provided for actuating each row of stations. As the capstan drive shafts 34 lie in a common horizontal plane, a pair of superimposed main drive shafts 29a, 29b are provided. According to this invention the main drive shafts 29a, 29b are superimposed and are equidistantly spaced above and below the capstan drive shafts 34, the main drive shafts 29a, 29b being journaled in bearing plates 39 connected between the plates 28 of the bracket 27. By providing each of the main drive shafts with a plurality of spacially disposed worms 40, equal to the number of stations in a row, and meshing the same with every other worm gear 41 connected to the capstan drive shaft 34, it will be noted that every station in the row is in driving connection with its respective main driving shaft.

In order to provide the power to each of the main drive shafts a power means, such as an electric motor 42 or the like, is utilized. As shown, the housing 24 is provided at each end at the top thereof with a pedestal 43 for supporting a motor, the motor shaft 44 being connected to its respectively driven main shaft by a belt 45 connecting cooperating pulleys 46 and 47 of motor shaft 44 and adjacent projecting end portions of the main driving shaft respectively in driving relationship.

Referring to Fig. 1 it will be noted that the wire W emanating from a source of supply, such as a furnace or enameling station or the like (not shown) is guided over a pair of master pulleys 48, 49 mounted on a bracket 50 adjacent an end portion of the frame, each master pulley having a plurality of grooves for handling a plurality of wire strands sufficient for accommodating the stations in a particular row. Thus, as the wire W is being fed, the same is taken off the master pulleys 48, 49 by a guide pulley 12 located at each station in the row and then looped around the capstan.

According to this invention the wire W is looped about the capstan 30 so that as the capstan is rotated, the wire W is fed into the container C from the top thereof. Feeding the wire into the container in this manner is found to be advantageous in that a container of greater depth may be utilized without increasing the overall height dimensions of the machine, i.e. the distance between the turntable and the center of the capstan. Also, a greater range of containers having varying depths may be utilized. With the container C, as illustrated in Figs. 1 and 2, secured on a carrier by means of a clamp 51 and rotated in the direction of the arrow, the wire leaving the top of the capstan will travel a minimum distance as it passes to and falls in coils into the container.

With the wire threaded over the master pulleys and guide pulleys and the main drive shafts in operation, a wire feeding and coiling operation may be performed at each station simultaneously and automatically with a minimum of personal attention on the part of the operator. As a result, during the normal operation of the instant device all that an operator is required to do is to remove the containers as they become full and substitute therefor an empty container.

In order that the operation of the entire row or bank of stations may not be interrupted during the removal

of a container from any one of the stations, a selecting means 52 is provided whereby the coiling operation at any station may be interrupted without effecting the coiling operation of the other stations. This is accomplished by including in the selecting means a clutch mechanism 53 for engaging and disengaging the carrier shaft 19 into and out of driving relationship with the capstan 30. Thus, when the clutch is disengaged the rotation of the turntable will cease, thereby affording the operator opportunity to release the clamp 51 and remove the container C when full and substitute therefor an empty one as the operation at the other stations is continuing. While the container is being changed, the capstan will continue to feed the wire. However, as the containers are quickly changed the operation is completed before an accumulation of wire is had. Thus, the operator simply gathers that portion of the wire which was fed as the container was removed and drops the same in the new container.

Referring to Fig. 3, the clutch mechanism 53 includes a pair of clutch members having cooperating means which when engaged with each other connects the carrier shaft 19 in driving relationship with the capstan 30. According to this invention the sprocket 38 forms one 25 member of the clutch mechanism and it is mounted on a reduced portion of the shaft so as to be freely rotatable or slippingly connected thereto. Projecting outwardly from the face portion 38a thereof, the member 38 is provided with a pair of opposed projecting pins 54. The cooperating clutch member consists of a flanged collar 55 keyed to the shaft 19, see Fig. 5, to rotate therewith and axially movable thereon for movement toward and away from the sprocket 38. As shown, the flange 55a of the collar 55 is likewise provided with a pair of opposed projecting pins 56, the pins 54 and 56 of each member being equidistantly disposed about the axis of the shaft 19. Thus, when the clutch member 55 is moved toward member 38 and into cooperating relationship therewith, the projecting pins 56 of member 55 engage the pins 54 of member 38, thus locking the shaft 19 in driving relationship with the capstan. When the member 55 is moved away from the sprocket or clutch member 38, the pins 54 and 56 are disengaged, causing the sprocket 38 to be freely rotated on the shaft, thereby permitting the turntable to be stopped.

In order to facilitate the engagement and disengagement of the clutch mechanism 53 at will, an actuating means is provided. As illustrated, the actuating means includes a split collar 57 connected to the axially movable clutch member 55. Connected to the split collar 57 is a slide rod 58 for moving the clutch member into and out of engagement relative to the sprocket 38.

As shown, the means for operating the slide rod 58 includes a foot pedal 59 pivotally mounted on a bracket 60 connected to the base 15 adjacent its respective station, the pedal 59 having a cam 61 for engaging the end of the rod 58. Thus, as viewed in Figs. 3 and 4, when the foot pedal 59 is kicked toward the frame as indicated by arrow a, the cam 61 engaging the end of the slide rod 58 causes the rod to move to the right, Fig. 3, against the action of spring 62 which normally maintains the clutch member 55 in engaged driving relationship. When this occurs, the turntable of the particular station is disengaged from driving position and ceases to rotate, thereby affording the operator opportunity to stop the coiling operation at the particular station.

To maintain the clutch disengaged and automatically lock the same in disengaged position while the operator performs the necessary function, the cam 61 is provided with a notch 61a to lock the slide bar against the action of the spring 62. Thus, to disengage the clutch the operator kicks the projecting portion 59a of the foot pedal to pivot the same until the rod 58 engages the notch 61a, and by kicking the opposite portion 59b of the pedal, the cam releases the rod so that the clutch is

rendered operative, the spring 62 biasing the clutch members into driving engagement.

From the foregoing description it will be apparent that the wire feeding and coiling operation can be performed at several stations under the supervision of a single operator. Not only does the apparatus of the instant invention reduce labor and handling to a minimum, but it also reduces the available space necessary for performing a plurality of feeding and coiling operations to a minimum. Consequently, enormous savings in cost can be had, which in turn is passed on to the consumers. Furthermore, the instant invention renders it possible to carry on the feeding and coiling operation in a more simple, expedient and efficient manner than was heretofore possible.

Variations and modifications may be made within the scope of the claims and portions of the improvements may be used without others.

I claim:

1. A wire handling mechanism comprising a common frame having a bank of feeding and coiling stations tandemly mounted thereon, each station comprising means including a capstan rotatably mounted on a horizontal axis about which a strand of wire is adapted to be looped for feeding the same from a source of supply to a container and for applying a cast to the wire to cause the wire to form coils in the container, means for rotating the container receiving the wire about an axis perpendicular to the axis of said rotary means, said wire being adapted to be fed into the container from the top of the capstan, means connecting said capstan in driving relationship with its respective container rotating means, and drive means common to all of said stations for driving said capstan and its respective connected container rotating means at relative rotative speeds, said connecting means including means for independently connecting and disconnecting the container rotating means from driving relationship with its respective capstan to facilitate removal of a container without interrupting the operations of the other stations.

2. A wire feeding and coiling mechanism comprising a common frame having a plurality of stations whereat wire emanating from a supply source is coiled into a container, each of said stations having means including a vertically disposed capstan about which the wire is looped for feeding the same and for applying a cast to the wire to cause the wire to form coils in the container, said capstan having a drive shaft for rotating said capstan in a substantially vertical plane, a substantially horizontal rotating carrier for rotatably supporting the container for receiving the wire mounted on said frame, said carrier being located below and adjacent the capstan so that the upper end of a container supported thereon is disposed adjacent the axis of rotation of the capstan and the container receives the wire from the top of the capstan, means for connecting said carrier in driving relationship with said capstan drive shaft, said connecting means including a carrier drive shaft and selecting means for selectively connecting said carrier drive shaft in and out of driving relationship with said capstan drive shaft so that said capstan and connected carrier are rendered operative at will to rotate at relative speeds, and

a main drive means common to all of said stations for driving the capstan drive shafts, said selecting means facilitating removal of a full container independently of interruption of the operations at the other stations.

- 5 3. The invention as defined in claim 2 wherein said
selecting means includes a member mounted on said carrier
drive shaft connected in driving relationship with said capstan shaft, said member being mounted to rotate
10 freely on said carrier shaft, a second cooperating member
keyed to said shaft to rotate therewith and mounted thereon for longitudinal movement relative thereto, and actuating means for moving said second member into and out of engagement with said first member at will, said members having cooperating means to
15 couple said members in driving relationship when said members are moved into driving relationship so that said carrier shaft is connected in driving relationship with said capstan shaft.

4. The invention as defined in claim 2 wherein said
20 selecting means includes a member mounted on said carrier drive shaft connected in driving relationship with said capstan shaft, said member being mounted to rotate freely on said carrier shaft, a second cooperating member
25 keyed to said shaft to rotate therewith and mounted thereon for longitudinal movement relative thereto, and actuating means for moving said second member into and out of engagement with said first member, each of
30 said members having cooperating pins connected thereto to couple said members in driving relationship when said members are moved into driving relationship so that said carrier shaft is connected in driving relationship with said capstan shaft.

5. The invention as defined in claim 2 wherein said
35 selecting means includes a first member mounted on said carrier drive shaft connected in driving relationship with said capstan shaft, said member being mounted to rotate freely on said carrier shaft, a second cooperating member keyed to said shaft to rotate therewith and mounted
40 thereon for longitudinal movement relative thereto, and actuating means for moving said second member into and out of engagement with said first member, said actuating means including a spring normally biasing said second member into cooperating relationship
45 with said first member, and an operating means for overcoming the spring action to disengage said members, said members having cooperating means to couple said members in driving relationship when said members are moved into driving relationship so that said carrier shaft
50 is connected in driving relationship with said capstan shaft.

6. The invention as defined in claim 5 wherein said
operating means includes a slide rod connected to said second member and a manually operated cam actuator
55 for moving said rod and connected second member to disengage said selecting means at will.
